CLAIM

The ornamental design for a video terminal, as shown and described.

DESCRIPTION

FIG. 1 is a front view of a video terminal showing the claimed design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a left front perspective view thereof; and,

FIG. 8 is a left rear perspective view thereof.

The broken lines shown in the drawings illustrate portions of the article and form no part of the claimed design.

1 Claim, 8 Drawing Sheets
